UNITED STATES PATENT OFFICE.

SAMUEL WILSON MORROW, OF BALTIMORE, MARYLAND.

BURNER.

1,348,574.

Specification of Letters Patent. Patented Aug. 3, 1920.

Application filed May 12, 1919. Serial No. 296,438.

To all whom it may concern:

Be it known that I, SAMUEL WILSON MORROW, a citizen of the United States, resident of Baltimore, Maryland, have invented 5 certain new and useful Improvements in Burners, of which the following is a specification.

This invention relates to a burner for use in cook stoves or heating stoves for burning oil as a fuel and it consists in the features and construction and arrangement of parts hereinafter described and particularly pointed out in the claims:

In the accompanying drawings:—

15 Figure 1 is a part vertical section and part elevation of the burner.

Fig. 2 is a plan view of a portion of the distributor plate.

Fig. 3 is a plan view of the burner.

20 Fig. 4 is a view of the combined fuel and water tank, connected up with the burner in a stove.

In these drawings 1 indicates a base member having seats at 2 for the hollow arms or 25 pipes 3 for conveying air to the point of combustion, these arms or pipes merging into a downwardly directed flared outlet portion at 4. The base member 1 is mounted in the stove to form a horizontal partition 30 between a lower chamber to which air is freely supplied and an upper chamber forming the fire box. The oil which may be kerosene, is delivered through a pipe 5 which connects with the central conduit or space 6 extending vertically through a distributor 35 plate 7. This plate has a depending boss at 8 which is screw threaded onto the upper end of the oil supply pipe and a shoulder at 9 rests upon the upper side of the base 40 member 1. The distributor plate has a central conical portion 10 and a dished rim portion 10'. At the upper portion of the conical center a flange 11 is formed extending in circular form around the central 45 opening 6 and this flange is provided with a series of notches or openings 12 regularly disposed about the flange so that the oil delivered through the central opening 6 may flow from the apex of the cone laterally and 50 downwardly along the inclined surface and through the various notches 12 so as to be distributed over the conical surface of the plate. In order to facilitate the even distribution of the oil at all points around the 55 conical plate I provide a channel at 13 just within the circular notched flange 11 so that

the oil will run around along this channel and will overflow through the distributor notches or openings 12. This will prevent oil being supplied in greater quantity to one 60 part of the conical surface than to another part because this channel will provide a circular conduit for the distribution of the oil immediately within the notched flange. A cap member 14 is arranged over the notched 65 flange so as to bear thereon and form a restricted space between its lower face and the conical face of the distributor plate and this cap member is concaved on its lower face so as to conform substantially to the conical 70 surface of the distributor plate and thus provide a space for the distribution and vaporizing of the oil in a comparatively thin sheet extending uniformly around the sides of the conical distributor member. 75 This cap member is carried by a pipe 15 extending down through the pipe 16 which extends through the top of the arms 3 and down to a point near the flaring discharge mouth 4 of said arms. The pipe 16 provides 80 an auxiliary air supply and water is introduced through the pipe 15 and is delivered to the openings 17 extending from the center of the cap member outwardly and downwardly so as to direct the steam generated 85 from the water to points just within the annular flange 11 so that combustion will be promoted at this point. The conical distributor plate is free from contact with the base 1 excepting at its center so that heat by 90 conduction will not be lost or drawn from the distributor plate except to the minimum degree, this being due to the fact that the distributor plate has but a small bearing connection at its central portion with the 95 base plate whereas its dished flange or flanged portion is free from connection with any adjacent part which would act to conduct the heat away.

It will be noticed that the upper surface 100 of the cap member 14 is of general conical shape with its apex directed upwardly and that this conical surface is surrounded by the flared wall of the air discharge mouth or portion 4. The oil delivered to the restricted 105 space between the conical distributor plate 7 and the cap 14 will be vaporized and the air issuing from the flaring mouth 4 downwardly and outwardly at the edge of the cap 14 and consequently at the edge of the 110 restricted vaporizing space will exert its force upon the fuel issuing under the edge

of the cap 14 and will mingle therewith in a thorough manner.

It will be noticed from Fig. 3 that the air pipes 3 taper from their sides to the center of the burner where the downwardly and outwardly flared discharge mouth 4 is located and these pipes present broad inner surfaces near their lower ends against which the flame or heat from the distributor plate 10 impinges so that the air passing through these pipes will be heated before reaching the discharge mouth 4.

Further it will be noticed that the dished form of distributor plate insures complete 15 combustion of the oil as any oil which may pass unignited from the edge of the cap plate will be retained by the dished portion long enough to be subjected to the heat and 20 flame and commingled with the air so that perfect combustion will be afforded.

At 18 I show a plate which may be formed integral with the hollow arms at the top thereof and extending horizontally from said arms. This plate will have a confining 25 effect on the heat and flame and will distribute the flame for the best heating effects.

It will be noticed that the air outlet 4 flares outwardly and downwardly and its wall is convergent in relation to the upper 30 inclined surface of the spreader 14 which is located substantially within this outlet. By this the air impinging upon the upper surface of the spreader is deflected outwardly and downwardly under pressure of the large 35 volume of air behind it so that it is discharged with force through the tapered annular outlet formed between the inclined upper surface of the spreader and the flar-

ing wall of the outlet and this air is discharged upon the thin sheet of oil as the 40 latter passes down the side of the distributor.

What I claim as my invention is:

1. In combination in a burner, a conical distributor having an upwardly directed oil conduit at its center, an overlying conical 45 spreader forming a narrow space between itself and the conical distributor for the discharge of the oil laterally in a thin sheet, air supply means having a downwardly directed flared discharge portion encircling the 50 upper portion of the spreader, the wall of said flared portion being disposed in proximity and at an acute angle to the distributor for causing a current of air to impinge upon the thin film of oil as it issues from beneath 55 the spreader.

2. In combination in a burner, a conical distributor having an upwardly directed oil conduit at its center, an overlying spreader forming a narrow space between itself and 60 the conical distributor for the discharge of the oil laterally in a thin sheet, air supplying means having an outlet directed downwardly upon the upper side of the spreader, said spreader deflecting the air downwardly 65 and outwardly upon the thin sheet of oil on the distributor after said oil issues from under the edge of the overlying spreader, the upper surface of the spreader inclining downwardly and the wall of the air outlet 70 being flared outwardly and downwardly and reaching to a plane near the plane in which the edge of the spreader lies, substantially as described.

In testimony whereof I affix my signature. 75
SAMUEL WILSON MORROW.
